(57) **CLAIM**

We claim the ornamental design for an animal feeder, as shown and described.

DESCRIPTION

FIG. 1 is a perspective view of an animal feeder of the present invention with a cover in a closed position;

FIG. 2 is a perspective view of an animal feeder of the present invention with a cover in an open position;

FIG. 3 is a perspective view of an animal feeder of the present invention with a cover removed for clarity of disclosure;

FIG. 4 is a front elevation view of the animal feeder of FIG. 1;

FIG. 5 is a rear elevation view of the animal feeder of FIG. 1;

FIG. 6 is a right side elevation view of the animal feeder of FIG. 1, the left side elevation view being a mirror image thereof;

FIG. 7 is a top plan view of the animal feeder of FIG. 1; FIG. 8 is a bottom plan view of the animal feeder of FIG. 1; FIG. 9 is a front elevation view of the animal feeder of FIG. 2;

FIG. 10 is a rear elevation view of the animal feeder of FIG. 2;

FIG. 11 is a right side elevation view of the animal feeder of FIG. 2, the left side elevation view being a mirror image thereof;

FIG. 12 is a top plan view of the animal feeder of FIG. 2; FIG. 13 is a bottom plan view of the animal feeder of FIG. 2;

FIG. 14 is a right side elevation view of the animal feeder of FIG. 3, the left side elevation view being a mirror image thereof; and,

FIG. 15 is a rear view of the animal feeder of FIG. 3. The features of the animal feeder shown in broken lines are for illustrative purposes only and form no part of the claimed design.
